UNITED STATES PATENT OFFICE.

RAYMOND E. HUNT, OF LAKESIDE, OHIO.

TOY BOAT.

Application filed December 24, 1920. Serial No. 432,920.

To all whom it may concern:

Be it known that I, RAYMOND E. HUNT, a citizen of the United States, and a resident of Lakewood, county of Cuyahoga, and 5 State of Ohio, have invented a new and useful Improvement in Toy Boats, of which the following is a specification, the principle of the invention being herein explained and the best mode in which I have contemplated 10 applying that principle, so as to distinguish it from other inventions.

The present invention, relating, as indicated to toy boats, is particularly directed to an improved miniature or toy boat constructed to permit of its operation both in 15 water and on a horizontal surface, such, for example, as the floor of a room. A further object of the invention is the provision of such an article that will float evenly in the 20 water and will have the appearance, both in the water and when on the solid surface, of the real ship of which it is a miniature. To the accomplishment of the foregoing and related ends, said invention, then, consists of 25 the means hereinafter fully described and particularly pointed out in the claim.

The annexed drawing and the following description set forth in detail certain mechanism embodying the invention, such 30 closed means constituting, however, but one of various mechanical forms in which the principle of the invention may be used.

In said annexed drawing:—

Fig. 1 is a side elevation of a boat embodying my improvements; Fig. 2 is a plan view of the same; Fig. 3 is a side elevation of another type of boat embodying the same invention; Fig. 4 is a plan view of the boat shown in Fig. 3; and Fig. 5 is a section on 40 the line 5—5, Fig. 2.

In Fig. 1 I have shown a toy boat constructed to resemble an American battleship, and consisting of a hull 1 of some buoyant material, such as thoroughly dried wood selected to be of substantially uniform density and specific gravity throughout. This hull member is flat, both on its upper and lower surfaces, and the bottom surface is provided with a plurality of recesses 2, in which 45 are mounted a series of rollers 3 arranged symmetrically with respect to the center line of the hull. These rollers are also of course mounted on parallel axes to permit of the boat having movement in either direction.

At the center of the upper portion the hull 50 is recessed at 4, and in the recesses thus pro-

vided are mounted a series of gun-carrying turrets 5, shown in plan in Fig. 2, to represent the secondary guns of an actual war ship. These turrets 5 carry miniature guns 60 6 and are pivotally mounted about parallel vertical axes in the form of pins 7.

Extending over the entire upper surface of the hull 1 is a deck 8 consisting of a single strip of relatively thin wood, which very 65 much enhances the appearance of the article, and serves as a smooth uniform support for the various elements which make up the superstructure of the boat. This deck 8 is also lined or marked off to represent planking to 70 further enhance its appearance. In the case of the battleship shown in Figs. 1 and 2 the superstructure consists of a longitudinally extending member 9, on which are removably and pivotally mounted masts 10 which 75 support gun-carrying "fighting tops." These "fighting tops" are also pivotally mounted on the masts 10 and are removable therefrom, the pivots therefor being made in the form of pins 12. Adjacent to either end of the member 9 are gun-carrying turrets 13 which are removably and pivotally mounted on axes in the form of pins 14 mounted on the deck 8. Each of the turrets 13 carries four guns 15, although the number is immaterial, but these turrets are so constructed 80 that the weight on either side of the axis or pin 14 is balanced so that when the turrets are swung to either side there is no change in the buoyancy of the vessel and no additional 85 weight brought to either side of the center line. The smokestacks 16 are also removably mounted on pins 17 carried on the superstructure 9, and the turrets, masts and smokestacks may all be removed when desired.

In Figs. 3 and 4 I have shown a boat representing in miniature a passenger liner, this boat having a hull 20 which is constructed in the same manner as the hull 1 100 of the boat previously described, and is similarly provided with rollers 21 to permit of its movement on a horizontal surface. The other features of this passenger boat are of course modified to properly represent 105 the appearance of an actual liner. The superstructure consists of a series of layers or plates 22, 23 and 24, on the upper of which are removably mounted smokestacks 25, while masts 26 and 27 are also mounted, the 110 former on the deck or hull of the boat and the latter upon the plate 23. The various

layers or plates which make up the super-
structure of this boat may be painted or
marked as indicated in Fig. 3 to represent
port holes, windows and doors as indicated.

5 It is extremely difficult in the manufac-
ture of toy boats to produce a boat which
will float evenly unless the boat is given
some form of keel, or unless some ballast is
provided in the lower part of the hull. It
10 is of course impractical to construct a boat
with a keel and also adapt it to move over
a solid surface and have the appearance of
a real boat. In order to accomplish these
desired results I have made the hull of
15 specially selected buoyant material, such as
dry wood of uniform density and specific
gravity throughout, and have kept the
weight of the superstructure below 25 per
cent of the weight of the hull. In
20 addition, the superstructure is exactly cen-
trally mounted on the hull of the boat, and
even in the case of the battleship shown,
which has turrets which swing to either
side, the weight of these turrets is so bal-
25 anced as not to affect the distribution of the
weight in the entire boat. In this way it is
possible to secure a perfect floating of the
boats in water, while at the same time the
height of the hull is kept to such propor-
30 tions that the boats have a natural and prop-

er appearance even when resting on the
floor.

Other modes of applying the principle of
my invention may be employed instead of
the one explained, change being made as re-
gards the mechanism herein disclosed, pro-
vided the means stated by the following
claim or the equivalent of such stated means
be employed.

I therefore particularly point out and dis- 40
tinctly claim as my invention:

In a combined toy land and water boat,
a combination of a buoyant hull of dry wood
of even density and thus of substantially
uniform specific gravity throughout, a su-
perstructure mounted centrally on said hull
of limited lateral extent as compared with
said hull, movable elements of irregular con-
figuration comprised in said superstructure
counterbalanced so as to at all times pre- 50
sent equal amounts of weight along the
median line of said hull, and rollers sym-
metrically disposed with respect to said me-
dian line so that said boat will be of rela-
tively stable equilibrium whether used as an 55
aquatic or as a land toy.

Signed by me, this 20th day of December,
1920.

RAYMOND E. HUNT.
